ROTISSERIE MOTOR HOUSING

David L. Painter, Chicago, Ill., assignor to The West Bend Company, West Bend, Wis., a corporation of Wisconsin

Filed Sept. 1, 1965, Ser. No. 86,797

Term of patent 14 years

(Cl. D26—5)

FIG. 1 is a front view of a rotisserie motor housing embodying my new design;

FIG. 2 is an end view thereof;

FIG. 3 is a top view thereof; and

FIG. 4 is a fragmentary view in section taken on line 4—4 of FIG. 1.

The elements shown in broken lines are included for illustrative purposes only.

I claim:

The ornamental design for a rotisserie motor housing, substantially as shown and described.
